UNITED STATES PATENT OFFICE.

EMRY BALOUGH, OF POUGHKEEPSIE, NEW YORK.

AUTOMOBILE WINDOW-OPERATING DEVICE.

1,393,484.

Specification of Letters Patent. Patented Oct. 11, 1921.

Application filed October 29, 1920. Serial No. 420,437.

To all whom it may concern:

Be it known that I, EMRY BALOUGH, a citizen of the United States and resident of the city of Poughkeepsie, in the county of 5 Dutchess and State of New York, have invented certain new and useful Improvements in Automobile Window-Operating Devices, of which the following is a specification.

10 The present invention relates to improvements in window operating devices, particularly for automobiles, one of the objects of the invention being to simplify the operation of the mechanism for opening and 15 closing windows of this type and for automatically locking the same in any desired position.

Another object of the invention is the provision of a window operating device of the 20 character mentioned, wherein all operating parts, except the operating handle, are concealed in the frame-work of the door from the view of the operator.

A further object of the invention is to 25 provide a window operating device of the type mentioned which is capable of manufacture on a commercial scale, or in other words one which is not so difficult to produce as to be beyond the reasonable cost of 30 such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

45 One of the many possible embodiments of the invention is illustrated in the accompanying drawings, in which:

Figure 1 is a central vertical section taken through a portion of an automobile door and window with the operating device constructed in accordance with the present invention in position thereon; Fig. 2 is a section taken on line 2-2 of Fig. 1; and Fig. 3 is an elevation of an automobile door and window from the inside, showing the improved operating device thereon.

Referring now to the drawings, the numeral 10 indicates an automobile door, such as are used on closed cars. This door is provided with a window opening 11, and 60 includes an outer door panel 12 and an inner lining board 13, the latter being spaced from said panel. In the vertical rails of the frame-work of the door are provided guide grooves 14, in which a window 15 is slidably 65 arranged. This window may include a sash, if desired, or it may be provided with a metallic channel member 16 inclosing its lower edge 17, as clearly shown in Fig. 1 of the drawings. So far described, the construction and operation of the elements are 70 well known and may be of any suitable or preferred type.

The window operating mechanism includes a bodily stationary screw-threaded spindle 75 18, which is rotatably mounted in a frame 19, the latter being secured in any suitable manner to the inner face of the lining board 13. The spindle extends vertically in the vertical center line of the door and is disposed below the window opening 11. The upper end of the frame 19 extends horizontally outward, as clearly shown at 20, serving as one of the bearings of the spindle. The lower end of the said spindle is provided with a recess 21, into which is fitted the pointed end of a supporting screw 22, the latter extending through the horizontally outwardly extending lower end 23 of the frame 19. A locking nut 24, in mesh 80 with the supporting bolt 22, may be provided for the well known purpose. The purpose of mounting the lower end of the spindle upon the screw bolt 22 is to permit of adjustment of the spindle, according to 85 the requirements. To the upper end of the spindle is keyed or otherwise fastened, immediately below the bearing 20, a bevel pinion 25, in mesh with a bevel gear 26. This gear is fixedly attached to a short 100 shaft 27, the latter extending through and beyond the lining board 13 and being rotatably mounted in the frame 19 and in a transverse frame member 28. This frame member is secured by screws 29, or otherwise, 105 to the frame 19 and serves, besides the function mentioned, as the means for holding the bevel gear 26 in proper position. To the free end of the shaft 27 is secured, in any suitable manner, a crank-handle 30, that extends through a plate 31, 110 which is fastened by screws 32, or otherwise,

to the inner surface of the lining board 13. In the construction shown herein the hub 33 of the crank-handle extends through the plate 31 and is prevented from disengagement therefrom by a countersunk head 34 on the said hub. The connection between the shaft 27 and the crank-handle is obtained by making the outer end of said handle of square cross-section and fitting it 10 into a similarly shaped bore in the crank-handle.

To the channel member is attached a downwardly extending lug 35, provided at its free end with an inwardly projecting extension 36. To this extension is fixedly secured a nut 37, the threads of which mesh with those of the spindle 18.

The operation of this device is as follows: In order to raise or lower the window, as the 20 case may be, the crank-handle is turned in the proper direction. The pitch of the screw-threads on the spindle 18 and, obviously, in the nut 37 in mesh therewith should be such that a self-locking structure is obtained. In this manner, the window will be locked against movement in any desired position without the aid of special fastening means.

From an inspection of the drawings it 30 appears that all the operating elements of the device, with the exception of the crank-handle 30, are concealed from view, they being disposed within the door, that is to say between the panel 12 and the lining 35 board 13 thereof. Notwithstanding this fact, access can be had to such elements of the device which may need lubrication from time to time. It is obvious that, by applying a few drops of oil through the window 40 opening to the spindle 18, an easy operation of the device will be obtained at all times.

It will be observed that an extremely simple and inexpensive means for effecting

the raising, lowering and locking of the window sash is provided, and that there is 4 practically nothing in the device herein described that is liable to get out of order or out of alignment.

The device, when once put in place, needs no other adjustment than the initial adjustments made, towit: The proper positioning of the spindle 18 in relation to the bevel gear 26. This adjustment is made by turning the screw bolt 22 in the proper direction and then screwing home the locking nut 24. 55

What I claim is:—

An automobile door having a window opening and including an outer door panel and an inner lining board spaced from said panel, a window pane slidably arranged in 60 relation to said opening and adapted to be brought out of alignment with the same into the space between said panel and lining board, a vertically extending frame secured to the inner face of said lining board, a vertically extending screw-threaded bodily stationary spindle journaled in said frame, a nut fixed to and projecting below said pane in mesh with said spindle, a transverse frame member rigidly secured to said first-mentioned frame, a shaft extending through and beyond said lining board rotatably mounted in said first-mentioned frame and in said transverse frame member, a bevel pinion fixed to said spindle, a bevel gear 65 fixedly attached to said shaft in mesh with said pinion, said bevel gear being disposed between said first-mentioned frame and said transverse frame member and held by the latter in position, and a crank-handle on 70 said shaft for actuating the latter.

Signed at New York, in the county of New York and State of New York, this 8th day of October, A. D., 1920.

EMRY BALOUGH.
